MERCURY ARC RECTIFIER

Charles K. Ittner, Troutdale, Oreg.

Application April 12, 1944, Serial No. 530,713

9 Claims. (Cl. 250—27.5)

1

My invention relates to high-voltage, high-current mercury arc rectifiers and has for its particular object the construction of a rectifier of this character which prevents arc-backs produced by mercury splashes which tend to strike the anode. Such arc-backs represent at the beginning a short circuit of the secondary of the rectifier transformer and result in service interruption. Many efforts have been made by the art to prevent splashing. Said efforts have been largely concerned with the provision of baffles for preventing splashing.

A mercury arc rectifier comprises, in its most elementary sense, a chamber adapted for high-level evacuation and includes a centrally disposed anode and a mercury pool cathode lying below and spaced from the anode. An evacuating conduit communicates with the chamber at a point adjacent the top of the latter, and pumping apparatus is connected therewith to maintain such evacuation.

In operation a rectifier of this character depends upon the vaporization of mercury, and it is necessary that the temperature of said chamber be regulated so as to produce condensation of said mercury vapors. Inasmuch as the chamber is subject to continuous evacuation, it follows that some substantial quantities of said mercury vapor are drawn into said evacuating conduit leading exteriorly from the chamber. Said vapors become cooled and condense, and if they flow back into the chamber, they do so as liquid mercury which drops substantially the height of the chamber. Said flow-back of mercury is not a continuous operation, but, normally, is initiated by vibration or jar. Thus, small cascades of mercury flow back at intervals. Of course, the mercury could be trapped to prevent said flow-back, but this would rapidly deplete the mercury in the cathode pool. The common practice, therefore, has been to provide baffles within the chamber to prevent splashing of said cathodes of liquid mercury.

I have discovered that if the evacuating line is tapped at a low point and a separate return line is provided, that the return flow of mercury can be caused to flow into the chamber at a point well below the horizontal plane of the anode to eliminate such mercury splashing and arc-backs. I preferably provide a return line which joins the evacuating line at a point externally of the chamber and which communicates with the interior of the chamber at a point below the normal level of the mercury in the cathode pool. I preferably provide a U-shaped trap to prevent mercury va-

2

pors from being drawn through said return line, which would tend to flow counter to the normal drain of liquid mercury flowing therethru.

The details of my invention and an explanation of a preferred embodiment thereof are herein-after described with reference to the accompanying drawing, in which the figure is a more or less schematic section through a typical mercury arc rectifier adapted for my invention.

10 The mercury arc rectifier illustrated is of the general type manufactured by Westinghouse Electric and Manufacturing Company, but is quite similar to similar rectifiers as manufactured by the General Electric Company and other manufacturers. All of said rectifiers have the same general characteristics. Said rectifier comprises a jacketed chamber 1, having an anode plate or cover 2 removably secured to the top thereof, Pendently supported centrally of said chamber 15 from said plate or cover 2 is an anode head 3 surrounded by a perforate anode shield 4. The cathode comprises a pool of mercury 5 held in a container 6 at the bottom of chamber 1. A baffle 7 lies intermediate said cathode and anode. Said shield and said baffle together tend to serve as splash baffles to prevent liquid mercury striking the surface of the anode head 3 to permit electron emission. Such a condition would result in an arc-back. It is recognized in the art that 20 every precaution should be taken to prevent the condensation or splashing of mercury on any part of the anode structure. It is true that control devices are provided which are adapted to prevent damage to the rectifiers. The action of said 25 control devices, however, does produce interruption of the power supply, and failure to maintain constant operation of said rectifiers requires that 30 further time elapse before they are in proper operating relation.

40 An igniter 8 is provided for initiating a cathode spot on the surface of the liquid mercury pool, which causes emission of free electrons into the evacuated interior of the chamber. These electrons will flow towards the anode in phase sequence as it becomes positive with respect to the cathode, and so current will flow from it to the cathode. The movement of electrons from the cathode spot to the anode bombards the mercury vapor, and as a result of this bombardment, 45 the mercury vapor is ionized and becomes a good conductor.

50 It is necessary that the vaporized mercury be condensed and that the temperature of the anode be maintained below the point of incandescence. Tank cooling coils 9 are, thus, arranged exterior-

ly of the chamber. Said tank cooling coils are preferably sheathed by a cover 10. Additional cooling coils 11 are preferably provided for the cathode. The coils thus form, more or less, a continuous water jacket about the chamber for adequately cooling the entire structure and provide large condensing areas for mercury vapor.

It is essential that the chamber be maintained at a high level of evacuation, and evacuating conduit 12 is in open communication with the chamber at a point adjacent the top thereof. It is common practice to connect a number of said rectifiers in bank, and, thus, said evacuating conduits are joined to a vacuum manifold. Because of the fact that the contents of the chamber are constantly being evacuated, it follows that some of the mercury vapor is drawn into the evacuation conduit and into the shutoff valve 13. These lie exteriorly of the rectifier and are at substantially lower temperatures than the interior of the chamber. The vapor quickly becomes liquified and cools in said conduit and in said shutoff valve.

It is essential that the mercury pool be constantly replenished. Thus, it is common practice to arrange said conduit 12 and the shutoff valve 13 to drain into the interior of the chamber. Thus, vapors are being pulled from the chamber, and condensate flows back along the floor of said conduit. It is essential that said evacuating conduit communicate with the chamber at a point adjacent the top of said chamber. Thus, when said condensate flows back into the chamber, it is required to fall substantially the height of the chamber. Efforts are made to confine the flow of mercury so that it will not strike the anode head to produce arc-backs. So many disturbing qualities exist within the chamber, however, that it frequently follows that said mercury splatters and particles strike the anode head even though seemingly efficient baffles are provided.

I have modified the standard structure by making the evacuating conduit a short run leading downwardly from the point 14 of communication with the chamber to the point 15 of communication with a return conduit 16. Said return conduit 16 preferably extends more or less vertically from the shutoff valve to a point adjacent the bottom of the chamber. Thus, any mercury which condenses in the customary shutoff valve or in the evacuating conduit 12 is caused to flow downwardly through the return conduit rather than laterally through the evacuating conduit. I preferably join the lower end 16a of the return conduit with the interior of the chamber through a U-shaped trap 17, preferably lying exteriorly of the chamber. Thus, said U-shaped trap houses a quantity of mercury 18 in addition to being in communication with the pool of mercury 5 forming a part of the cathode.

It is desirable that the evacuating conduit communicate with the interior of the chamber near the top thereof to minimize the amount of mercury vapor withdrawn from the chamber. By providing two points of communication—one with the evacuating conduit and another with the return conduit—I would provide two alternate paths through which mercury vapor could reach the shutoff valve. The quantity of mercury 18 lying within said U-shaped trap effectively bars the outward flow of mercury vapor through the lower end of the return conduit, however. Thus, mercury vapor leaves the chamber through the evacuating conduit 12, and any quantity of mer-

cury condensing in said evacuating conduit, said shut-off valve or in adjacent connections tends to return to the chamber through the return conduit which has a straight vertical run. Also, the outward flow of mercury vapor from the evacuating conduit tends to prevent any small particles of condensed mercury from being diverted to flow into the chamber at point 14. That is, the evacuating conduit 12 is in open communication and is unrestricted by baffles, traps and the like, and thus the suction pump is entirely free to evacuate the chamber without loss of efficiency which would follow the use of baffles or other obstructions.

I have not attempted to show in the drawing the various connectors and terminals by which electrical connections are made, because they will readily be understood by persons skilled in the art. My invention is directed only to the control of the flow of mercury vapors from the chamber and the return flow of condensed mercury to keep the cathode pool replenished without producing arc-backs in the rectifier.

I claim:

1. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, communicating at its upper end with said evacuating conduit intermediate the ends of the latter and with the interior of said chamber, at a point spaced substantially below the point of communication of said evacuating conduit with said chamber.

2. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, the upper end of said return conduit being in communication with the evacuating conduit at a point lying exteriorly of said chamber, and said mercury return conduit communicating with the interior of said chamber at its lower end.

3. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open com-

munication with said chamber, of a vertically extending mercury condensing and return conduit, the upper end of said return conduit being in communication with the evacuating conduit at a point lying immediately exteriorly of said chamber, and said mercury return conduit communicating with the interior of said chamber at its lower end.

4. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, the upper end of said return conduit being in communication with the evacuating conduit at a point lying exteriorly of said chamber, and at a horizontal level below the point of communication of the evacuating conduit with the interior of said chamber, and said mercury return conduit communicating with the interior of said chamber at its lower end.

5. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, the upper end of said return conduit being in communication with the evacuating conduit at a point lying exteriorly of said chamber and at a horizontal level below the point of communication of the evacuating conduit with the interior of said chamber, the floor of said evacuating conduit sloping downwardly from said latter point to its point of communication with the mercury return conduit, and said mercury return conduit communicating with the interior of said chamber at its lower end.

6. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, the upper end of said return conduit being in communication with the evacuating conduit, and said mercury return conduit terminating at its lower end in a U-shaped trap communicating with the interior of said chamber.

7. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, the upper end of said return conduit being in communication with the evacuating conduit, said mercury return conduit terminating at its lower end in a U-shaped trap communicating with the interior of said chamber at a point lying adjacent the level of the pool of mercury.

8. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, the upper end of said return conduit being in communication with the evacuating conduit, and said mercury return conduit terminating at its lower end in a U-shaped trap communicating with the interior of said chamber at a point lying below the level of the pool of mercury.

9. The combination with a mercury arc rectifier of the character described comprising a chamber adapted for evacuation, anode and cathode elements, the cathode element including a pool of liquid mercury, said rectifier being characterized by producing vaporization of said mercury during the operation thereof, said pool of mercury lying below and being spaced substantially from the anode element, and a conduit leading from the interior of said chamber to an evacuating device arranged at the exterior thereof, said conduit being in open communication with said chamber, of a vertically extending mercury condensing and return conduit, the upper end of said return conduit being in communication with the evacuating conduit, and said mercury return conduit communicating with the interior of said chamber at a point substantially below the plane of the anode element.
